FURNITURE SUPPORT JOINTED TO FRAME

Johan Elias Svedberg, Stockholm, Sweden

Application July 18, 1945, Serial No. 605,720
In Sweden April 19, 1944

3 Claims. (Cl. 311—110)

1

My invention relates to furniture of wood or fibrous material, and more particularly to cabinets and tables of various kinds. A main object of the invention is to provide articles of furniture which may be delivered in a dismounted state from the factory to the retailer or even to the individual user to be assembled by him into a finished perfect product, without any special skill in the particular field being required for this purpose. A further object of the invention is to provide an article of furniture the individual parts of which are adapted to be taken apart so as to call for a minimum of space in transport, in order then to be erected into a perfectly stable product by the simplest means.

It is known to retain table-tops, for example, on the framework carrier, by means of blocks located on the lower side between the table-top and the framework. These blocks are secured by means of screw bonds, generally in the table-top, and have a projection entering a groove in the framework. The blocks, however, only have for their object to prevent the table-top from being lifted off the framework, and for this reason they do not contribute to the rigidity of the furniture, special measures being therefore taken to ensure rigidity. In fact, the blocks are adapted to permit a sliding movement between the table-top and the framework, in the plane of the top.

Further objects and advantages of the invention will be apparent from the following description considered in connection with the accompanying drawing which forms a part of this specification, and of which:

Fig. 1 is a perspective view of a portion of a cabinet, constructed according to the invention, certain parts being cut away.

Fig. 2 is a sectional view through a portion of the cabinet in a plane parallelling the door-side of the cabinet.

In the embodiment according to Figs. 1 and 2, the cabinet comprises a door 10, a top member 12, three side members 14 and a bottom member (not shown). The top member 12 and the bottom member each consist of a square frame, the frame members 16 of which may be rigidly interconnected at the corners in any known manner. The wood fibres of the various frame members extend in the ordinary manner in the longitudinal direction thereof. Rigidly connected with the frame members is a covering board 18, which may be composed of a number of veneer layers. Likewise, the side members 14 each consist of a square frame of frame members 20 and a covering board 21. The cabinet is delivered from the

2

factory with the abovementioned door, top member, bottom member and side members in a completely finished but non-assembled state. Since they are substantially plane and of little thickness, the entire article of furniture calls for considerably less space than if it were erected in the ordinary manner.

The side members, the top member and the bottom member are joined together by the recipient with the aid of the means according to the invention. This means consists of an elongated locking bar 22, which is adapted to bear closely against surfaces 24, 26 of the frame members 16 and 20, respectively, in the right-angled corner 15 formed between these members in the erecting operation. The bars 22 are connected with the frame members of the top member and of the bottom member, respectively, by means of screw bonds 28. The bar 22 may be provided with a projection 30 laterally of the contact surface 26, said projection fitting accurately into a groove in the frame members 20 of the side members 14. The frame members 16 are each formed with a groove 32, the inner side wall of which is flush with the contact surface 26, and the outer side wall of which is formed by a projection 36 which does not reach as far as to a plane coinciding with the surface 24. The frame members 20 are shaped correspondingly, the same fitting into the grooves 32 with projections 38, while the covering boards 21 extend for a distance over the lateral surface of the frame member 16. The side members 14 will thus form grooves 39 adapted to receive the projections 36 of the frame members 16.

The joining device according to the invention renders the cabinet perfectly rigid. Thus the projections 30 and 36, 38, respectively, prevent relative movement between the top and side members in planes parallelling the faces of the cabinet. Furthermore, the cabinet becomes perfectly stable in the diagonal direction, the great surfaces 24, 26 of the bars 22, bearing on the frame members 16, 20 cooperating in solving this problem. Thus, if the cabinet is subjected to a diagonal pressure in the direction of the arrow in Fig. 2, such pressure will be taken up at the surfaces 24, 26 by the bar between the top and side members situated right opposite the bar 22 shown in the figure as well as by the bar situated at the bottom member right beneath the bar shown. As will be seen, the erection of the members may take place without any skilled labour being required. The bars 22 are concealed within the cabinet, and no joint will be visible in members

with untreated external surfaces. A constant intimate contact is ensured between the surfaces 24, 26 of the bars and the respective frame members by the fact that the frames cannot swell and shrink to any appreciable extent under the influence of moisture, inasmuch as the fibres of the frame members always extend in the longitudinal direction. The only transverse wood material having an effect on the contact in consideration is located between the screw bonds 28 and the surface 26. The width of this wood material is an insignificant fraction, however, of the whole width of the square frame. In this case, a sufficiently stable article of furniture is obtained by arranging bars 22 along the frame members between the side members and the top member and the bottom member except on the door side.

The cabinet according to Figs. 1 and 2 is provided with a number of drawers 40. These drawers are inserted into grooves 42 in rails 44. The rails 44 enter in turn into the end portions of grooves 46 on the insides of the vertical frame members 20. The rails 44 may loosely engage the grooves 46, the drawers 40 then serving to retain the rails in their proper position. No special operations will be required for this in the assembling of the cabinet.

The bar 22, which extends along the whole or the major length of two furniture members to be interconnected, may be divided into two or more elements. In place of screw bonds, it is possible in certain cases to make use of nail bonds, even if the former are to be preferred. The bar 22 may be glued to the frame member 20, the projection 30 being then omitted, if desired.

It will be understood that the embodiment of the invention disclosed in the drawing is for purposes of illustration only and that various changes may be made in the invention without departing from the spirit and scope thereof, and therefore the invention is not limited by that which is shown in the drawing and described in the specification but only as indicated in the appended claims.

What I claim is:

1. An article of furniture of the cabinet type comprising panels providing side walls and a top,

said panels including rigid frame members extending along marginal portions thereof and rigid dismountable joints, the inner face of one of said panels having a marginal tongue extending longitudinally of the frame member and an adjacent longitudinally extending groove, the marginal edge of a second panel having a tongue extending longitudinally of the frame member in spaced relation to the outer face of the panel and a longitudinally extending groove disposed between the last mentioned tongue and said outer face, the tongue of each panel being received respectively in the groove of the other panel, an elongated locking bar extending longitudinally of and engaging the inner faces of both of said frame members, and means for securing said bar to both of said frame members whereby said panels are locked together to provide a unitary structure.

2. An article of furniture as defined in claim 1 in which the means for securing the locking bar to the frame members comprises a tongue and groove connection between said bar and one of said members and screw threaded fastening means for securing said bar to the other member.

3. An article of furniture as defined in claim 1 in which the means for securing the locking bar to the frame members comprises an adhesive joint between said bar and one of said members and screw threaded fastening means for securing said bar to the other member.
